CIRCULAR KNITTING MACHINE

Robert Kirkland Mills, Sherwood, Nottingham, England, assignor to Hosiery Developments Limited, Nottingham, England

Application January 5, 1932, Serial No. 584,867
In Australia September 10, 1931

21 Claims. (Cl. 66—41)

The invention of this case relates to circular knitting machines and consists in improvements having relation to that invention described and claimed in my co-pending application for patent filed January 8, 1930, which application has since matured into Patent No. 1,844,781, dated February 9, 1932.

The principal object of the present invention is to provide a circular knitting machine embodying means for producing a knitted fabric wherein the tendency to rove or ladder is minimized or eliminated, and a particular object is to produce non-ladder or ladder-resisting fabric of the type described in the specification accompanying the application for patent Serial No. 419,228, filed by me January 8, 1930.

Broadly the present invention consists of a circular knitting machine embodying needles having a plurality of latches spaced one below another on the needle shank, thread-feeding means, means for effecting relative movement between the thread feed and the needles for stitch production, means operating at predetermined times to feed thread above the uppermost latch to produce an ordinary knitted stitch and means operating at other predetermined times to feed thread between the latches to produce a locked or tied stitch.

The different types of stitches, i. e. locked or tied stitches and ordinary or tying stitches are produced by providing needle-operating cam mechanism so designed or operated as to displace the needles at predetermined times to an extent for receiving thread above the uppermost latch, i. e. in the needle hook, and at other predetermined times to displace said needles to a comparatively greater extent so as to take thread between the latches.

This variation in the degree of motion imparted to the needles may be effected by the employment of two needle-operating cams of different construction or design, or by periodical adjustment of one and the same cam or a part or parts associated therewith. The operation of the aforesaid cam or cams is preferably such as to cause the locked or tied and the ordinary or tying stitches to be produced alternately; and where two needle-operating cams are installed in the machine, that for producing the locked or tied stitches may be displaceable into and out of operative position.

The machine in accordance with this invention also, in some instances, includes means whereby when a needle-operating cam for producing locked or tied stitches is movable into and out of an operative position, a sinker cam and thread feed-

ing device associated with said needle cam are simultaneously moved into and out of operation.

For the purpose of more fully describing the nature of this invention reference will now be made to the accompanying drawings, wherein:—

Figure 1 illustrates a double latch needle suitable for use in a machine in accordance with this invention.

Figure 2 illustrates in perspective the top of the needle cylinder and sinker carrier in a circular knitting machine in accordance with one embodiment of the present invention, the latch ring and thread-feeding means being omitted.

Figure 3 illustrates in side elevation one construction of automatically displaceable needle-operating cam mechanism for producing locked or tied stitches.

Figure 4 is a plan view of Figure 3 showing the cam mechanism in the operative position.

Figure 5 is an interior elevation, somewhat enlarged, of the cam mechanism shown in Figures 3 and 4, the path traversed by the needle butts being indicated.

Figure 6 is a sectional elevation on A—A of Figure 5.

Figure 7 illustrates in elevation mechanism for imparting motion to a sinker cam which operates in conjunction with the locked stitch needle-operating cam mechanism shown in Figures 3 to 6.

Figure 8 is a plan of Figure 7.

Figure 9 is an enlarged plan of an adjustable carrier for the sinker cam.

Figure 10 is a sectional elevation on B—B of Figure 9, a sinker and thread being shown coacting with a needle.

Figure 11 illustrates in part sectional elevation a thread feed associated with a locked stitch needle-operating cam and means for controlling the movement of said feed.

Figure 12 is a plan of Figure 11.

Figure 13 is an enlarged sectional elevation through the thread feed shown in Figure 11.

Figure 14 illustrates seven successive steps in the production of an ordinary knitted stitch followed by a locked or tied stitch.

Figure 15 illustrates diagrammatically two sets of superimposed cams applicable for use in a circular knitting machine in accordance with another embodiment of the present invention.

Figures 16, 17, 18 and 19 are sectional detail views illustrating the co-operation between the cams and needles at the positions P¹, P², P³ and P⁴ respectively in Figure 15.

Figures 20 and 21 illustrate a needle-operating cam adjustable for producing both ordinary

110

stitches and locked or tied stitches at will, Figure 20 showing the cam adjusted for producing ordinary stitches and Figure 21 the position of the cam for producing locked stitches.

6 Figure 22 illustrates in part sectional elevation one side of a circular knitting machine in accordance with a further embodiment of this invention, such machine being adapted for knitting a selvaged and fashioned non-ladder fabric.

10 Figure 23 is another part sectional elevational view of the machine shown in Figure 22.

Figure 24 illustrates diagrammatically needle-operating cams employed in the machine shown in Figures 22 and 23.

15 Figure 25 illustrates an adjustable needle-operating cam applicable for use in a circular machine for knitting fabric by reciprocation, the cam being shown in position for producing ordinary stitches.

20 Figure 26 is another view of the cam shown in Figure 25 but illustrating same adjusted for producing locked or tied stitches.

Figures 27 and 28 illustrate means for automatically adjusting the cam device shown in Figures

25 25 and 26.

In machines according to the present invention latch needles are employed which are distinguished from ordinary latch needles in that same are provided with a plurality of latches spaced one below another on the needle shank.

30 A suitable needle is shown by way of example in Figure 1 of the drawings, there being two independently pivoted latches 1, 2 spaced one below the other on the shank 3 so that when the top latch 1 is lowered and the bottom latch 2 raised, the latter abuts against or overlaps the latch 1, and said top latch when raised closes the hook 4 in the usual manner.

One construction of circular knitting machine 40 will now be described with reference to Figures 2 to 13 of the drawings, which machine embodies two needle-operating cams, one functioning to produce ordinary stitches and the other locked or tied stitches, said two cams being arranged in

45 the machine to operate on the needles substantially closely in succession. In Figure 2 the position of the ordinary stitch cam is indicated by the comparatively low needle wave at OC, while the position of the locked stitch cam is indicated by 50 the comparatively high needle wave at LC, a separate thread being fed to the needles at each cam.

The stitch cam for producing the ordinary stitches is of any customary design and consequently needs no particular description here; it being sufficient to say that said cam functions to project a needle to an extent sufficient to clear an existing thread loop thereon below the latch 1 and take new thread in its hook and subsequently retracted to knock over. The production of locked stitches, however, necessitates a specially constructed or designed cam which operates to project a needle to an extent sufficient to clear the old loop below both latches 1 and 2 and receive new thread between the latches instead of in the needle hook.

Where the two cams are installed in the machine to produce ordinary and locked stitches alternately, as is the case in the machine illustrated in Figures 2 to 13, the successive motions imparted to a needle are as shown in Figure 14. In this figure, the first position reading from the left shows the needle raised by the ordinary stitch cam to clear an old loop 5 and receive new thread 6 in the hook 4, said cam then low-

ering the needle to knock over at the second position and form a normal stitch. At the third position the locked stitch cam has commenced to operate on the needle and raised same to clear the retained loop 6 below the top latch 1 followed by a short downward motion (effected by a small auxiliary cam hereinafter described) to ensure the loop 6 passing to the rear of the raised bottom latch 2 (see fourth position). The upward motion is then continued to the fifth position wherein further thread 7 from a second feed is fed between the latches and the loop 6 cleared beneath the lower latch 2. On the subsequent downward motion the cleared loop 6 is passed over the overlapping latches 1, 2 into the needle hook (see position six) thus drawing the new loop 7 through said loop 6, the continued downward movement knocking over said new loop 7 and causing same to become tied on said loop 6.

To enable the production of locked stitches to be effected and discontinued as and when desired means are advantageously provided for withdrawing the locked stitch cam and its associated thread feed out of operation at predetermined intervals so as not to function on the needles and for returning same to the operative position without discontinuing the production of ordinary or unlocked stitches.

One suitable construction of locked stitch cam device and means for moving same into and out of operation is illustrated in Figures 3 to 5. In these figures the locked stitch cam device comprises four cam bits 8, 9, 10 and 11 arranged for displacement radially of the machine, two of the cam bits 8 and 9 being mounted on slidable block 12 and the remaining two cam bits 10 and 11 being mounted on slidable block 13, said blocks 12 and 13 having tail pieces 12a and 13a respectively which are guided in their radial sliding movement within fixed brackets 14 and 15. When the cam device is in operation the first cam bit 8 operates on the needle butts to raise the needles to the third position shown in Figure 14, the cam bit 9 being an auxiliary cam which produces a short downward motion of the needles to bring the old thread loop between the latches as in the fourth position in Figure 14; the third cam bit 10 then raises the needles to the feeding position and the final cam bit 11 withdraws the needles to the knocking over position.

The needles in one half of the cylinder may be provided with long butts and the remainder with half butts in the manner customary in circular machines for knitting stockings where a proportion of the needles are raised out of action for knitting by reciprocation during the heel and toe. When the radially displaceable cam device requires to be brought into operation after having been withdrawn, the inward movement is accomplished in two steps through lever mechanism from the main cam drum 16 of the machine. The first step is effected during the time the short butts are passing the cam and causes said cam first to coat with and operate the long butt needles, the second step being effected to complete the inward movement while the cam is coacting with said full butts, thus causing said cam to operate both long and short butt needles. If desired the locked stitch cam may be approximately half the thickness of the normal stitch cam. The withdrawal of the cam is effected in one motion.

The locked stitch cam device is projected into

and retained in its operative position by springs 17 (Figure 6), a screw adjustment 18 accurately determining the extent to which the cams are projected, and the radial displacement of the two 5 cam blocks 12 and 13 to withdraw the cams out of operation may be effected through the intermediary of two longitudinally slid able bars 19, 20, each having a bevelled end face coacting with an 10 upstanding stop or the like 21 associated with each tail piece 12a, 13a of the sliding blocks 12, 13, or with a roller 21a on said stop. The opposite end of each of the two bars 19, 20 is furnished with a roller or truck 22, each truck coacting with the upper curved or bevelled end of a vertical or substantially 15 vertical lifting rod 23, two of such rods being provided, one appertaining to the bar 19 and the other to the bar 20. The lower end of each lifting rod 23 (which may be bevelled) coacts with the cam drum 16 on which are provided two suitably spaced cam rises 16a. The cam rises 16a are, as aforesaid, furnished with two steps so that the falling movement of the lifting rods 23 from their respective cam rises 16a is accomplished in two steps and permits of the cam 20 springs 17 effecting an initial movement of the locked stitch cam device while same coacts with the short butts and a final movement while said cam coacts with the long butts.

A sinker cam is also moved radially into and 30 out of operation in synchronism with the radially displaceable locked stitch cam above-described. To this end the sinker cam 24 (Figures 9 and 10) is secured on the underside of a radially displaceable carrier plate 25 which is guided in its movement in fixed guides 26, a plate or portion 35 27 intermediate the carrier 25 and cam 24 coacting with a peripheral flange 28 to determine the degree of outward movement of the carrier 25 and cam 24, while an adjustable screw stop 29 on the carrier 25 is also adapted to coact with said flange 28 to determine the degree of inward movement of the sinker cam. The sinker cam 24 is so shaped that when same is fully projected inwardly the butts 30a of the sinkers 30 travel round the machine without being effected by said cam, it being understood that the sinker cam is moved to its projected or inoperative position when the locked 45 stitch cam before-described is inoperative.

To withdraw the sinker cam to its operative position, i. e. to a position wherein the sinker butts 30a are caused to traverse the curved face of said cam, pivoted lever mechanism is provided operated by a lifting rod 31 from the aforesaid cam drum 16. In the arrangement illustrated in the drawings a centrally pivoted lever 32 is connected at its one extremity to an upstanding pin 33 on the sinker cam carrier 25 and coacts at its other extremity with an adjustable screw stop 34a provided on an arm 34 connected to a vertical pivot or rotatable member 35 to the lower end of which member is connected a second arm 36 coacting at its extremity with the upper curved or bevelled end of the lifting rod 31. A spring 37 associated with the upstanding pivot 35 serves to maintain the arm 36 in engagement with the upper end of the lifting rod 31, while a second spring 38 associated with the pivot of the lever 32 maintains one end of said lever in engagement with the stop on the arm 34 and also functions normally to press the sinker cam 24 and its carrier into the inwardly projected position. When, however, the lifting rod 31 coacts with a rise 16b on the cam 16 the aforesaid lever mechanism is displaced to withdraw the sinker cam 24 into the operative position.

Additionally, fine adjustment of the sinker cam is effected in a circumferential direction, preferably by screw mechanism, thus enabling the length of thread loops drawn and the tightness of stitches produced to be controlled. In one method of doing this a screw-threaded spindle 39 terminating in a knurled knob 40 is mounted within an axially rotatable element 41 on the carrier plate 25, the threaded portion of said spindle 39 being screwed through an enlarged head 42 of a pin 43 which projects down through an arcuate slot 44 in the carrier 25 and is screwed into the sinker cam 24. By rotating the spindle 39 the head 42 of the pin 43 is traversed axially on said spindle and the cam 24 thereby adjusted circumferentially of the machine. One or more additional headed screws 45 passing through an elongated slot or slots 46 in the carrier 25 and screwed to the cam 24 function to assist in the guiding of said cam during its adjustment.

Simultaneously with the radial movement of the locked stitch cam and sinker cam, a thread feed associated with said cams is moved into and out of operation. In one method of accomplishing this the thread feeder may comprise a vertically guided and displaceable plate member 47 adapted to be depressed from the non-feeding position to the feeding position against resistance of a spring 48 (Figure 13) by a lever 49 which extends substantially horizontally from 100 and is pivoted about a spindle 50 which constitutes the common axis or fulcrum for pivotally displaceable thread feeders 51 serving to feed thread to the needles at the position of the ordinary or unlocked stitch cam.

While the locked stitch cam is in operation, the feeder 47 associated therewith is maintained depressed by causing a lifting rod 52 to coact with and ride upon a cam rise 53 on the aforesaid cam drum and press upwardly upon a tail portion 49a of the aforesaid pivoted lever 49 coacting with the said feeder. When, however, the cam and feeder are to be withdrawn from operation,—say for example when the machine reciprocates for producing the heel and toe of a 110 stocking,—the lifting rod 52 moves off the cam rise 53, thus permitting the pivoted lever 49 to swing up under the influence of a spring 54 and releasing the thread feed 47 which is raised by its associated spring 48. The movement of the feeder can be adjusted by a screw device 55 on the coacting pivoted lever 49.

In a modified construction of circular machine for producing non-ladder fabric two superimposed cam races may be installed in the machine, each cam race embodying a cam for producing ordinary or normal knitted stitches and a cam for producing locked stitches, the position of the ordinary stitch cam OC in one cam race registering with or being in vertical alignment with the locked stitch cam of the other race, see Figure 15. In such a machine the double latch needles are each provided with two vertically spaced butts, selected of said needles N (Figures 16 and 18) having long upper butts 56 and short lower butts 57, while the remaining needles N' (Figures 17 and 19) have the longer butts 56 lowermost and the shorter butts 57 uppermost. In Figure 15 groups of needles N are shown alternating with groups of the needles N', only the butts of the needles being shown for the sake of clearness, and each group being shown by way of example as consisting of three needles. The thickness or dimension radially of the machine of the cam bits which com-

prise the ordinary stitch cams OC is greater than the thickness of the cam bits comprising the locked stitch cam LC. The arrangement is such that at one knitted course the longer butts 5 of the needles N will coat with an ordinary stitch cam, while the shorter butts of said needles will miss the locked stitch cam of lesser thickness and thus produce ordinary knitted stitches; the needles N¹ at the same course being operated 10 to produce locked stitches by the engagement of their lower long butts with the locked stitch cam. At the next succeeding course the needles N, which previously produced ordinary stitches, will be raised to a greater height by the engagement 15 of their long upper butts with a locked stitch cam and thus produce locked stitches, while the needles N¹ will produce ordinary stitches by reason of the fact that their upper short butts will miss the locked stitch cam and 20 their lower long butts will be operated upon by the ordinary stitch cam. Thus it will be appreciated that by an arrangement of cams as above together with needles having long and short butts, selected of said needles will, on alternate 25 courses, produce locked stitches while the remaining needles produce ordinary stitches, and on the remaining alternate courses the operation will be reversed, that is to say, the needles which on the last preceding course knitted plain stitches 30 will produce the locked stitches and vice versa.

In Figures 20 and 21 of the accompanying drawings a needle cam device is illustrated applicable for use in a circular knitting machine and capable of being adjusted so as to vary the 35 height to which the double latch needles are projected, and by so doing produce either ordinary or locked stitches at will. In the construction illustrated, the peak portion 58 of the cam C is vertically slidable within a slot or recess 59 40 in said cam, a second and auxiliary cam bit 60 being also advantageously slidable within a second slot or recess 61. Two cam bits 58 and 60 are connected by vertical arms 62 to a part 63 carrying a truck or roller 64 which coacts with a travelling chain 65, said travelling chain having at predetermined intervals high links 66 which are adapted to coat with the aforesaid truck 64. Suitable spring means such as 67 operate to maintain the truck 64 in engagement with a travelling chain.

When the truck 64 is in its lowermost position clear of the high link 66 the two cam bits 58, 60 are lowered within their slots to the position shown in Figure 20 and in this position the needle butts traverse the path indicated by the arrows and produce ordinary knitted stitches. When, however, a high link 66 engages with the truck 64 the two cam bits 58, 60 are raised against the resistance of a spring 67, thus causing the needles to traverse the path indicated and rise to a greater height so as to produce locked stitches in the manner previously described. The auxiliary cam bit 60 operating in conjunction with the peak cam bit 58 serves to bring an existing loop on the needles positively between the two latches during the upward motion of the needles to take thread when producing a locked stitch. The travelling chain 65 may be intermittently traversed by pawl and ratchet mechanism 68, or any other approved mechanism may be employed for this purpose. If desired, the high links 66 may be so spaced on the chain as to cause ordinary and locked stitches to be produced on alternate knitted courses.

In a further modification a circular knitting

machine may be employed which operates to produce flat fashioned or shaped fabric with selvedged edges by imparting continuous rotary motion to the needle-operating cams. On such a machine, which is illustrated in Figures 22, 23 and 24, a plurality of independent selvedged blanks can be simultaneously produced by employment of two continuously and oppositely rotating needle cams 69 and 70 (see Figure 24) and by also employing two continuously and oppositely rotating sinker cams, said oppositely moving cams being arranged to pass one another at positions in the machine void of needles.

All of the needles in the machine are operated by each of the stitch cams, which cams operate alternately, independent thread-feeding means being provided for each fabric blank being produced, and each of said feeds (one of which is shown at 71 in Figure 22) being traversed first in one direction and then in an opposite direction so as to cause successive courses to be knit in opposite directions.

In order to produce on this type of machine alternate courses of locked or tied stitches, the cams 69 and 70 are differently designed, the cam 69 being of the customary formation applicable for producing ordinary or unlocked stitches, while the cam 70 is designed to raise the double latch needles to a higher position than the cam 69 so as to cause the thread to be fed between the latches instead of into the needle hook and by so doing produce tied or locked stitches.

It will be appreciated that as the cams 69 and 70 operate on the needles in succession, alternate courses of locked or tied stitches are produced.

The width of the fabric, or each fabric portion being knitted, is varied during production, this being conveniently effected by simultaneously raising from an inoperative to an operative position a predetermined number of needles at predetermined intervals at each side of the group or groups of operative needles so as to widen the fabric to the required extent.

For this purpose a pair of lifting elements 72 may be provided (Figures 22 and 23) one of such elements being fixed to a circumferentially toothed ring 73 and the other to a second circumferentially toothed ring 74 accommodated within an annular recess in the first-named ring 73. These two lifter rings 73, 74 are raised and lowered at predetermined intervals by means of a plurality of suitably spaced rollers 75 which are normally accommodated within recesses 76 in a relatively stationary ring or member 77 but are caused at the required intervals to ride upwardly out of said recesses 76 and thereby lift the rings 73, 74 with the lifting elements 72.

The movement of the rollers 75 may be effected from a projection 78 carried by and rotating with the lower cam box 79, said projection 78 coacting with a radially slidable arm 80 linked to a lower radially extending arm 81, which arm carries a bevelled nose portion 82 adapted when the arm 81 is moved radially inwards to rotate the ring 83 on which the rollers 75 are mounted.

The lifting rings 73, 74 are provided with circumferential ratchet teeth continually engaged by a pair of clawker arms 84 and through the medium of these clawker arms 84 the lifter rings 73, 74 are rotated step by step in opposite directions to displace the lifting elements 72 to a position beneath successive needles for raising the same.

The operation of the clawkers 84 for rotating the lifting rings may be effected intermittently from the aforesaid projecting elements 78 on the

cam box 79 through the intermediary of mechanism similar to that employed for displacing the aforesaid lifting rollers 75.

Another type of circular machine which may be employed is that wherein flat selvedged non-ladder fabric is produced by reciprocation of the needle-operating means, and in such a machine a needle-operating cam device is conveniently employed which can be adjusted at predetermined intervals to produce either locked or unlocked stitches.

One such adjustable cam device applicable to a circular reciprocating machine is illustrated in Figures 25 to 28 of the accompanying drawings.

15 The centre cam 85 up which the needles rise to clear their old loops and take fresh thread, is provided with a vertically displaceable peak portion 86 which when in the lowered position (as shown in Figure 25) causes the needles to rise to a height sufficient to receive new thread in the needle hooks and produce ordinary or unlocked stitches. When, however, the peak portion 86 is fully raised to the position shown in Figure 26, the needles are raised to a position in which thread is fed between the two latches and locked or tied stitches are thus produced, it being understood that in the production of locked stitches the cam is travelling in the direction indicated by the arrow in Figure 26.

30 When producing the locked stitches the needles are caused to traverse a small auxiliary cam 87 during their upward movement to take thread, the purpose of said auxiliary cam being, as before-stated, to ensure that the old thread loops on the needles take up a position between and at the rear of the needle latches so as to lower the bottom latch during the subsequent upward movement of the needles.

Adjusted simultaneously with the peak portion 45 86 of the cam 85 are two other cam elements 88, 89, which elements, when the peak portion 86 is in the lowered position, are moved downwards to the position indicated in Figure 25 so as to cause the needle butts to traverse the path indicated in broken lines in said figure, whereas when the peak portion 86 is fully raised to produce locked stitches the two adjustable cam elements 45 88, 89 are raised to cause the needle butts to traverse the small auxiliary cam along the path indicated in broken lines in Figure 26.

If now the peak portion 86 and other displaceable cam elements 88, 89 are adjusted on the termination of each knitted course, it will be appreciated that during the motion of the machine 55 in one direction ordinary stitches are produced and during the opposite motion locked stitches are produced, and in this way fabric is made having locked stitches on alternate knitted courses. One method of automatically adjusting the cam device on each knitted course is illustrated in Figures 27 and 28. The displaceable peak portion 86 of the centre cam 85 together with the two movable cam elements 88, 89 may be mounted on a single vertically slideable block or frame 90, the cam elements 86, 88 and 89 being secured to said block by pins 91 coacting with vertical slots 92 in the fixed portions of the cam device.

70 Travelling with the cam box within which the needle-operating cam device is installed is a horizontally slideable member 93 having an upstanding cam rise 94, said member 93 being frictionally carried within suitable bearings 95 secured to the cam box. On the termination of the motion of the cam box in one direction the frictionally carried member 93 may coact with a relatively

stationary stop or lug 96 and by so doing slidably displace the member 93 to a position wherein a roller or truck 97 associated with the vertically displaceable cam block 90 moves downwardly from off the cam rise 94 on the member 93 either by gravity or under the influence of springs 98, thus lowering the peak portion 86 and cam elements 88, 89 to a position for producing ordinary stitches. At the termination of the movement of the cam box in an opposite direction the slideable member 93 is also displaced in an opposite direction by engagement with a stop member 99 and in so doing the cam rise 94 is moved beneath the roller 97 so as to raise the block 90 and with same the cam elements 86, 88 and 89, the needle-operating cams being then adjusted to produce locked or tied stitches.

If at any time it is required to continue producing successive courses of ordinary or unlocked stitches for any predetermined length of time, this can readily be accomplished by displacing the stop member 99 to a position wherein same will not coact with a sliding member 93. One suitable method of accomplishing this is by slidably mounting the stop 99 and causing same to be pressed upwardly to an operative position by a rotary cam member 100 or equivalent device, a spring 101 functioning to lower the stop 99 to an inoperative position when same is out of engagement with the cam rise on the member 100.

I claim:—

1. In a circular knitting machine, needles having a plurality of latches spaced one below another on the needle shank, thread-feeding means, means for effecting relative movement between the thread feed and the needles for stitch production, means operating at predetermined times to feed thread above the uppermost latch to produce ordinary knitted stitches and means operating at other predetermined times to feed a different thread between the latches of the same needles to produce locked or tied stitches.

2. In a circular knitting machine, needles having a plurality of latches spaced one below another on the needle shank, thread-feeding means, cam mechanism operating to displace the needles relatively to the thread feed for stitch production, said cam mechanism functioning at times to displace the needles to receive thread above the uppermost latches and produce ordinary knitted stitches and at other times to displace said needles to receive other thread between the needle latches and produce locked or tied stitches by passing a loop of thread through and also around another thread loop.

3. In a circular knitting machine, needles having a plurality of latches pivoted one below another on the needle shank, thread feeding means, a needle-operating cam device functioning to displace the needles so as to clear old thread loops thereon beneath the lowermost latch and receive new thread between the latches and subsequently to draw a loop of the new thread through and pass same closely around the old loop so as to tie the two loops one upon another, an additional needle-operating cam device for the same needles, additional thread feeding means associated therewith and said additional cam device functioning to produce ordinary knitted stitches.

4. A circular knitting machine as claimed in claim 3 and wherein the two needle-operating cam devices function in succession alternately to produce locked or tied stitches and ordinary or tying stitches.

5. In a circular knitting machine, needles hav-

ing a plurality of latches pivoted one below another on the needle shank, thread feeding means, a needle-operating cam device functioning to displace the needles so as to clear old thread loops thereon beneath the lowermost latch and receive new thread between the latches and subsequently to draw a loop of the new thread through and pass same closely around the old loop so as to tie the two loops one upon another, an additional needle-operating cam device for operating the same needles, additional thread feeding means associated therewith, said additional cam device functioning to produce ordinary knitted stitches, and means whereby the cam device for producing the locked or tied stitches together with the thread feed associated therewith is movable into and out of operative position.

6. In a circular knitting machine, needles having a plurality of latches pivoted one below another on the needle shank, thread-feeding means, a needle-operating cam device functioning to displace the needles so as to clear old thread loops thereon beneath the lowermost latch and receive new thread between the latches and subsequently to draw a loop of the new thread through and pass same closely around the old loop so as to tie the two loops one upon another, an additional needle-operating cam device for operating the said needles, additional thread-feeding means associated therewith, said additional cam device functioning to produce ordinary knitted stitches, a sinker cam associated with the locked stitch cam, means for moving said locked stitch cam and its associated thread feed into and out of operative position, and means for moving said sinker cam into and out of operative position in synchronism with said locked stitch cam and its associated thread feed.

7. In a circular knitting machine, needles having a plurality of pivoted latches spaced one below the other on the needle shank, two-needle-operating cams for the said needles, a thread feed associated with each cam, one of said cams functioning to displace the needles to a position wherein thread is fed into the needle hooks so as to produce ordinary knitted stitches, the said cam functioning to displace the needles to a comparatively greater extent to receive thread between the latches for the production of locked or tied stitches, said cams operating on the needles in succession, means for radially displacing the locked stitch cam into and out of operative position, a sinker cam associated with the locked stitch cam, means for radially displacing said sinker cam into and out of operation and means whereby the locked stitch cam together with the associated sinker cam and thread feed are simultaneously moved into and out of operation.

8. A circular knitting machine as claimed in claim 7 and including link and lever mechanism operated from a control drum radially to displace the locked stitch cam and its associated sinker into and out of operation.

9. A circular knitting machine as claimed in claim 7 and including means for variably adjusting the degree of radial displacement of the locked stitch cam device.

10. A circular knitting machine as claimed in claim 7 and including spring means associated with the locked stitch cam device against the influence of which spring means said cam device is displaced out of operation.

11. A circular knitting machine as claimed in claim 7 and including means for effecting fine adjustment of the sinker cam associated with the

locked stitch cam both radially and circumferentially of the machine.

12. In a circular knitting machine, needles having a plurality of pivoted latches spaced one below the other on the needle shank, two needle-operating cams for all of said needles, a thread feed associated with each cam, one of said cams functioning to displace the needles to a position wherein thread is fed into the needle hooks so as to produce ordinary knitted stitches, the second cam functioning to displace the needles to a comparatively greater extent to receive thread between the latches for the production of locked or tied stitches, said two cams operating on the needles in succession, means for radially displacing the locked stitch cam into and out of operative position, a sinker cam associated with the locked stitch cam, means for radially displacing said sinker cam into and out of operation, means whereby the locked stitch cam together with the associated sinker cam and thread feed are simultaneously moved into and out of operation, lever mechanism operating to displace the thread feed associated with the ordinary stitch cam, lever mechanism operating to displace the thread feed associated with the locked stitch cam and both of said lever mechanisms being controlled from one and the same control member.

13. In a circular knitting machine, needles having a plurality of pivoted latches spaced one below another on the needle shank, two superimposed cam races, each cam race embodying a needle-operating cam functioning to produce ordinary stitches and a needle-operating cam functioning to produce locked or tied stitches, means functioning to feed the same thread to needles operated by an ordinary stitch cam and needles operated by a locked stitch cam, means whereby selected needles are operated by the locked stitch cam of the one race to produce locked stitches at one position in the machine and other selected needles are operated by the locked stitch cam of the second race to produce locked stitches at another position in the machine and means whereby all of the needles so operated are also operated upon by the ordinary stitch cams so as successively to produce locked stitches and ordinary stitches.

14. A circular knitting machine as claimed in claim 13 and wherein a needle-operating cam in one cam race for producing ordinary stitches registers with or is aligned with the needle-operating cam in the second cam race for producing locked stitches.

15. In a circular knitting machine, needles having a plurality of pivoted latches spaced one below another on the needle shank, each needle being provided with two spaced butts of unequal length, selected of the needles having long upper butts and short lower butts, the remaining needles having short upper butts and long lower butts, two superimposed cam races, each race embodying a needle-operating cam for producing ordinary stitches and a needle-operating cam for producing locked stitches, thread-feeding means, the long and short butts on the needles being operated upon by the cams of both races and said operation being such that selected needles on alternate courses produce locked stitches and the remaining needles produce ordinary stitches, while on the remaining alternate courses this operation is reversed.

16. In a circular knitting machine, needles having a plurality of latches pivoted one below another on the needle shank, thread feeding

means, an adjustable needle-operating cam device, means for adjusting said cam device to a position wherein the needles are operated to receive thread above the uppermost latch and produce ordinary stitches and means for adjusting the cam device to another position wherein the needles are operated to receive thread between the latches and produce locked or tied stitches.

17. A circular knitting machine as claimed in claim 16, wherein the needle-operating cam has an adjustable peak portion, said peak portion being movable to either of two positions, in one of which the needles are projected to an extent to receive thread between the needle latches for producing locked stitches, while in the other position the needles are projected to a comparatively shorter distance for receiving thread above the uppermost latch and producing ordinary stitches.

18. In a circular knitting machine, needles having a plurality of pivoted latches spaced one below another on the needle shank, a needle-operating cam device, thread-feeding means associated with said cam device, said cam device incorporating an adjustably displaceable portion, a spring-influenced member associated with said displaceable portion, a travelling member functioning at predetermined intervals to displace said member and cam portion against the spring influence, said cam portion when moved to one position operating upon the needles to project same to an extent for receiving thread between the needle latches and locked stitches are produced and when moved to another position causing said needles to be projected to an extent for receiving thread above the uppermost latch so as to produce ordinary stitches.

19. In a circular knitting machine, needles hav-

ing a plurality of latches spaced one below another on the needle shank, thread-feeding means, two needle-operating cams, means functioning simultaneously to rotate said cams in opposite directions, one of said cams operating to displace the needles to a comparatively greater distance than the other cam, the cam which projects the needles to the greater distance producing locked or tied stitches, the cam which projects the needles to the comparatively smaller distance producing ordinary stitches, and said cams operating alternately on the needles so as to produce the locked or tied stitches on alternate courses.

20. In a circular knitting machine, needles having a plurality of pivoted latches spaced one below another on the needle shank, thread-feeding means, a needle-operating cam, means whereby flat selvedged fabric is produced on the machine by relative reciprocation between the needles and needle-operating cam and means whereby at predetermined intervals said needle-operating cam is automatically adjusted to produce locked or tied stitches by projecting the needles at the thread-feeding position to an extent greater than the normal so that the thread is received on the needles between the latches thereof.

21. In a circular knitting machine as claimed in claim 20, the provision in the needle-operating cam of a plurality of displaceable portions and means operating automatically to displace said portions at predetermined intervals from a position wherein the cam functions to produce ordinary stitches to a position wherein the said cam functions to produce locked or tied stitches and vice versa.
